UNITED STATES PATENT OFFICE.

LAURENCE TER MAAT, OF CHICAGO, ILLINOIS.

CLOTHES WRINGER.

Application filed May 18, 1921. Serial No. 470,602.

To all whom it may concern:

Be it known that I, LAURENCE TER MAAT, a citizen of the United States of America, residing at Chicago, in the county of Cook 5 and State of Illinois, have invented certain new and useful Improvements in Clothes Wringers, of which the following is a full, clear, and exact specification.

This invention relates to clothes wringers 10 and its object is to provide a power driven wringer with means for facilitating delivery of wet articles to the rolls and at the same time obviate the necessity of putting the hands near the rolls, with consequent risk 15 of injury, when feeding articles thereto; also to increase the efficiency of the wringer by providing means for making it certain that all the water pressed out by the rolls will flow into one tub and that the articles passed 20 through the rolls will deliver into another.

I have accomplished these objects by slightly modifying the construction and arrangement of the wringer rolls and by equipping the wringer with a safety feeding apron 25 of special construction, including edges which cooperate with the rolls in a manner to cause water to be retained on the apron and articles placed thereon to be fed to the rolls.

With these main and other incidental objects in view, my invention consists of the organization, details of construction, parts, or their equivalents, hereinafter described, and more particularly defined in the claims. 30

Referring to the drawings:

Fig. 1 is a plan view of a wringer constructed according to my invention.

Fig. 2 is a front elevation.

Fig. 3 is an enlarged vertical section on the line 3—3 Fig. 1; and

Fig. 4 is an enlarged detail view of the rolls with the apron shown in cross section.

I have illustrated my invention in connection with a power driven wringer mounted 45 on a suitable support A and driven through the gear case B in the usual manner. Ordinarily, the wringer will be positioned between two tubs, C, D, as in Fig. 1.

The wringer frame may be of the usual 50 construction illustrated, the various parts of which need not be described. On the inner side of each of the vertical end members of the frame and near their lower ends I secure a pair of horizontally extending bracket members 10 which extend in parallel relation an equal distance from each side of the

wringer frame beneath the rolls. On the ends of the members 10 there are journaled rollers 11 and spaced inwardly a short distance from these are second rollers 12 which 60 are mounted in adjustable bearings controlled by set-screws 12^a and act as tension controlling means for the apron. The wringer rolls, ordinarily of equal length, are modified to carry out my invention by making the upper roll somewhat shorter than the lower one so that the lower roll projects a little beyond the upper roll at each end, as at 13. The wringer rolls and rollers 11 and 12 just described serve to support an 70 endless feeding and delivering apron 14 which passes between the wringer rolls, around the supporting rollers 11 and over the idler tension rollers 12. As evident from the drawings, the relation of the supporting 75 rollers to the wringer rolls is such that both the upper and lower runs of the apron inclines downwardly and outwardly from the rolls on either side and water carried on the apron will therefore not drip therefrom except at the ends over the tubs. 80

The apron 14 is of special construction and constitutes an important part of my invention. It may be of any preferred waterproof fabric or composition, its distinctive 85 feature being that its edges are enlarged for thickened and therefore raised above the surface of the apron. The upper rolls of the wringer extend from one raised edge of the apron to the other and the raised edges 90 are brought into contact with the ends of the upper roll as they pass over the lower one, as indicated at 15, Fig. 4. In the present instance I have shown the apron edges as thickened by means of a cord 16 inclosed 95 in hems on the edges of the apron. When the apron is stretched over its supports, the thickened edges, which press on the rollers 11 and on the lower wringer roll, are forced to project above the surface of the apron 100 which therefore presents a trough-like shape. Incidentally, the corded or thickened edges reinforce the apron, prevent the stretching, and, due to contact with the ends of the upper roll, keep the apron in proper position. 105

It results from the construction described that water pressed from the clothes cannot flow over the edges of the apron, but must flow down the apron into the tub, and also that articles passing through the rolls will be 110 retained on the apron and properly delivered. It further results that the articles

placed on the lower part of the apron will be raised and guided thereby to the rolls, making it unnecessary for the person feeding the wringer to bring hand or fingers 5 within dangerous distance of the rolls.

It will therefore be evident that I have provided a novel construction which increases the efficiency of this class of devices and makes for safety in their operation, and

10 I claim as my invention:

1. In a wringer, the combination with the pair of wringer rolls of an inclined movable conveyor apron engaged between the rolls and extending from end to end thereof, and 15 means comprising a projecting portion on each edge of the apron engaging the ends of the upper roll for guiding the apron and preventing escape of water over the apron edges.

20 2. A wringer comprising a pair of wringer

rolls, one of which projects beyond the other, supports mounted beneath the rolls and extending horizontally to each side thereof, apron carrying elements mounted between the ends of said supports, an endless apron 25 trained over said carrying elements and passing between said rolls, a projecting portion on each edge of the apron in engagement with the ends of the shorter roll, and an apron-tensioning device mounted intermediate the ends of said supports.

3. A wringer comprising a pair of wringer rolls, one of said rolls projecting beyond the other, and an endless apron supported to pass between said rolls and formed with 35 projecting edges engaging the ends of the shorter roll.

In testimony whereof I affix my signature.

LAURENCE TER MAAT.
